DIRECT CURRENT TIMER

BACKGROUND OF THE INVENTION

1. Field of the Invention

This invention relates in general to timing circuits and in particular to a direct current timer that may be adjusted so as to cycle over a broad timing range.

2. Description of the Prior Art

Actuators for solenoid valves as for example in lubricating applications, have been generally energized manually. However, it is desirable to provide automatic energization of a solenoid which controls a lubricator, for example.

SUMMARY OF THE INVENTION

The present invention comprises a direct current timer connected in circuit with a pump solenoid valve and which may be adjusted over a wide range so as to energize the solenoid valve at a selected rate. The rate may be adjusted by a switch that allows the solenoid to be cycled between the ranges of 1 to 50 cycles per hour, for example. The solenoid valve may also be energized manually if desired and the time of energization of the valve is selectable and will be fixed as the cycle rate is varied.

The timer of the invention uses semiconductor components such as unijunction transistors, silicon control directifiers and zener diodes to provide an improved timing circuit.

Other objects, features and advantages of the invention will be readily apparent from the following description of a certain preferred embodiment thereof taken in conjunction with the accompanying drawing, although variations and modifications may be effected without departing from the spirit and scope of the novel concepts of the disclosure, and in which:

BRIEF DESCRIPTION OF THE DRAWING

The drawing is a schematic view of the direct current timer of the invention.

DESCRIPTION OF THE PREFERRED EMBODIMENT

The figure illustrates a pair of power terminals 10 and 11 to which a suitable direct current voltage is applied as for example in the range from 20 to 30 volts. Terminal 10 is a positive terminal and terminal 11 is a negative terminal. A fuse 12 is connected to the positive terminal 10 and the anode of a diode D₁ is connected to the other side of the fuse. A load 13 has one side connected to the cathode of the diode D₁ and the other side is connected to a normally open manual switch 20 that has its other side connected to negative terminal 11. When the manual switch 20 is closed the load 13 which may be a solenoid valve for a lubricator or other device is energized. A normally closed switch 21 has one side connected to the load 13 and the other side is connected to the anode of an SCR2 which has its cathode connected to terminal 11. A diode D₂ has its anode connected to switch 21 and its cathode connected to the cathode of diode D₁. The resistor R₁ is connected in parallel with the load 13 and the switch 21. A condenser C₁ is connected from the anode of SCR2 to the anode of an SCR1 and a resistor R₂ is connected from the anode of SCR1 to the cathode of diode D₁. The cathode of SCR1 is connected to terminal 11. The gate electrode of SCR1 is connected to the first base of a unijunction transistor T₁. A resistor R₃ is connected between terminal 11 and the first base of the transistor T₁. The second base of transistor T₁ is connected to a resistor R₄ which has its other side connected to the anode of SCR1. A resistor R₅ is connected from the anode of SCR1 to the emitter of transistor T₁. A condenser C₆ is connected from the emitter of transistor T₁ to terminal 11. SCR2 has its anode connected to the normally closed switch 21 and its cathode is connected to terminal 11. The gate of SCR2 is connected to the cathode of a diode D₃ which has its anode connected to the first base of a unijunction transistor T₂. The first base of the transistor T₂ is connected to terminal 11 through a resistor R₆. The second base of transistor T₂ is connected through a resistor R₇ to one

side of a resistor R₈ which has its other side connected to the cathode of diode D₁. A condenser C₂ is connected between the second base of transistor T₂ and the emitter of a transistor T₃. A resistor R₉ is connected from the junction point between resistors R₈ and R₁₀ and the second base of transistor T₃. A resistor R₁₂ is connected between the first base of transistor T₃ and terminal 11. Terminal 11 is connected through a zener diode D₅ to a lead 21. Lead 21 is connected to a selector switch 22 that may be controlled by knob 23. The switch 22 connects a selected one of a plurality of resistors R (timing) to lead 21. The other side of the timing resistors are connected together and to a resistor R₁₁ which has its other side connected to the anode of a diode D₄ which has its cathode connected to the emitter of transistor T₂. A pair of timing capacitors C₄ and C₅ have first sides connected to terminal 11 and are connected in parallel with their other sides connected to the anode diode D₄.

In operation the load 13 will be energized at a rate dependent upon the setting of the switch 22 and it might vary for example, between the range of 1 to 50 cycles per second depending upon the value of the resistance selected with the switch 22 from the timing resistor bank. It is to be realized, of course, that the manual switch 20 may be closed for energizing the load 13 but unless the manual switch has been selectively closed by the operator the switch will be open. When power is applied at terminals 10 and 11, as for example, by closing an external on-off switch, not shown, the load 13 will be immediately energized and will remain energized for a preset time that might be, for example, 30 seconds. The solenoid valve will then be deenergized and will be energized after the initial time at a rate dependent upon the setting of the switch 22 which selects a particular timing resistor in combination with the timing capacitors C₄ and C₅.

The diode D₁ provides reverse polarity protection and the resistor R₈ reduces the voltage applied between terminals 10 and 11 to a smaller value which is controlled by the zener diode D₅. For example, if the power applied to terminals 10 and 11 is 24 volts DC the voltage across the diode D₅ might be 18 volts, for example, for the timing circuit. When the power is applied to the input terminals the capacitor C₁₀ momentarily supplies current to the gate of silicon controlled rectifier SCR2 to turn on the SCR and this allows current to pass to the load 13 through the switch 21 and the SCR2. Simultaneously capacitor C₆ will charge through resistors R₂ and R₅ for approximately 30 seconds before firing unijunction transistor T₁. When unijunction transistor T₁ fires it turns on SCR1. When SCR1 turns on, the charge on capacitor C₁ is connected across SCR2 which momentarily stops the flow of current through SCR2 and turns it off and the load 13 off. SCR1 will remain on until SCR2 is fired to turn SCR1 off.

Capacitors C₄ and C₅ charge through the timing resistors and the resistor R₁₁ and by selecting different timing resistors the charging rate may be changed. For example, to obtain long time cycles as, for example, 1 hour, the timing resistor must be quite large as for example, approximately 60 megohms. The unijunction T₂ will not fire until the voltage on capacitor C₄ and C₅ has reached a sufficiently high level. The unijunction including the transistor T₃ forms an oscillator which applies negative pulses to the base of the transistor T₂ which momentarily lowers the voltage requirement to allow unijunction T₂ to fire if the voltage across the timing capacitor C₄ and C₅ has reached a sufficiently high level. The output pulse of unijunction T₂ when fired is applied to the gate of SCR2 through the diode D₃ to again turn on and once again repeat the sequence of events.

Thus, the unijunction transistor T₂ comprises the primary timing circuit with the timing resistor and the capacitors C₄ and C₅ and the timing cycle is selected by moving switch 22 by a knob 23 to select a desired timing cycle. The transistor T₃ forms an oscillator to lower the V_D of the unijunction T₂ momentarily which allows for long time cycles using large resistance values.

The SCR's 1 and 2 form a static switch or flip-flop which turns the load on and off.

The transistor T_1 provides a time delay to allow recycle of the SCR static switch and might be set, for example, for a 30 second delay.

In a particular embodiment the following component values were utilized.

R1 R2 1500 Ohms

R3 47 Ohms

R4 680 Ohms

R5 470 K Ohms

R6 47 Ohms

R7 47 Ohms

R10 1000 Ohms

R8 330 Ohms

R9 680 Ohms

R11 220 K Ohms

R12 47 Ohms

and the timing resistors vary from 1 megohm to 60 megohms.

T_1 is a type 2 N 2646, T_2 is a type 2 N 1671 B, T_3 is a 2 N 2646, SCR1 and SCR2 are type C6F, diode D_1 is a type 1 N 2069, diode D_2 is a 1 N 2069, diode D_3 is a 1 N 2069, diode D_4 is a 1 N 2069, diode D_5 is a zener type Z4XL18.

Thus, it is seen that the timing circuit of this invention provides means for periodically energizing a load 13 for a preset time determined by the time delay established by the circuit associated with the transistor T_1 . The primary timing circuit comprising the timing resistors and capacitors C_4 and C_5 may be varied to have a period from 1 minute to 1 hour depending upon the setting of the switch 22 which connects one of the timing resistors in circuit. The timing cycle might be, for example, 1, 2, 3, 4, 6, 8, 10, 12, 15, 20, 30, 40 cycles per hour. The circuit illustrated operates satisfactorily over an ambient temperature range of -50° to $+150^\circ$ Fahrenheit.

Although the invention has been described with respect to preferred embodiments it is not to be so limited in changes and modifications may be made therein which were in the full intended scope as defined by the appended claims.

What is claimed is:

1. A circuit for controlling the application of power to a load from a power circuit comprising:

a first silicon controlled rectifier with its anode and cathode connected in series with said load and said power supply; a first capacitor connected between said power supply and the gate of said first silicon controlled rectifier;

- 4
- 5 a second silicon controlled rectifier with its cathode connected to the cathode of the first silicon controlled rectifier;
- 5 a second capacitor connected between the anodes of said first and second silicon controlled rectifiers;
- 10 a first resistor connected between said anode of said second silicon controlled rectifier and one terminal of said power supply;
- 10 a first unijunction transistor with a first base connected to the gate of said second silicon controlled rectifier;
- 15 a second resistor connected between said gate and cathode of said second silicon controlled rectifier;
- 15 a third capacitor connected between said cathode of said second silicon controlled rectifier and the emitter of said first unijunction transistor;
- 20 a third resistor connected between the emitter of said first unijunction transistor and the anode of said second silicon controlled rectifier;
- 25 a fourth resistor connected from the second base of said first unijunction transistor and the anode of said second silicon controlled rectifier;
- 25 a second unijunction transistor connected across said power supply with a first base connected to the gate of the first silicon controlled rectifier;
- 30 a fourth capacitor connected between the second side of the power supply and the emitter of said second unijunction transistor;
- 30 a plurality of timing resistors with first sides connected to the emitter of said second unijunction transistor;
- 35 switch means connected to one side of the power supply and engageable with one of said timing resistors;
- 35 a third unijunction transistor with its bases connected across said power supply;
- 40 a fifth capacitor connected between the emitter of said third unijunction transistor and the second side of the power supply; and
- 40 a sixth capacitor connected between the emitter of the third unijunction transistor and the second base of said second unijunction transistor.
2. A circuit according to claim 1 comprising a manual switch connected between the anode and cathode of said first silicon controlled rectifier.
